Original application February 24, 1938, Serial No.
192,310. Divided and this application Decem-
ber 23, 1939, Serial No. 310,668

2 Claims. (Cl. 242—65)

This invention relates to apparatus for winding fabric supplied either in short or continuous lengths.

An object of this invention is to provide means whereby fabric may be wound on a mandrel, severed at selected points and winding begun on a succeeding mandrel without stopping the machine.

This application is a division of our copending application Serial No. 192,310 filed February 24, 1938, now Patent No. 2,187,644 issued Jan. 16, 1940, which was a continuation in part of our original application Serial No. 691,522, United States Letters Patent 2,109,469, filed September 23, 1933.

Fig. 1 is a cross section of part of a fabric finishing machine embodying our invention;

Fig. 2 is a sectional view of a manually operated wind-up and arbor changing device;

Fig. 3 shows the apparatus of Fig. 2 immediately after the material has been cut;

Fig. 4 is a sectional view of an automatically operated wind-up and arbor changing device;

Fig. 5 shows the apparatus of Fig. 4 immediately after the material has been cut; and

Fig. 6 is a plan view of the apparatus of Fig. 4.

The material to be wound passes partly around a driven roller 86 after which it is wound on mandrel 178. The latter has pintles resting in inclined grooves 207 of an extension bracket 208. While the winding is in progress the fabric on the mandrel bears against driven roller 86 which serves to rotate the mandrel and overlying fabric. As the body of fabric increases in size the pintles of the mandrel move along grooves 207 and away from roller 86 (Figs. 2 and 4).

Recesses 209 in the top of bracket 208 receive the pintles of an unfilled mandrel 210 which is held in readiness to be placed in position to receive the fabric when mandrel 178 is removed (Fig. 2). There are downwardly extending grooves 211 in the brackets 208 which at the bottom communicate with grooves 207.

When mandrel 178 has been filled it is moved along the brackets 208 to extensions 800 at the outer ends of grooves 207, thus taking roll 26 out of contact with driven roller 86 and away from the receiving position. The new mandrel 210 is then lifted from the notches 209 and inserted in the upper ends of grooves 211. Mandrel 210 thereupon slides down grooves 211 and into engagement with roller 86. The material may now be severed by a cutter of the type shown in United States Letters Patent 1,745,476. In using a cutter of this sort fabric is permitted to

accumulate between roll 26 and roller 86 and to drop downward until it lies over cutter bar 310. The operator then moves cutter 310 across the cutter bar severing the material (Fig. 3) after which the end of the following strip of material is thrown over the new mandrel 210 which immediately begins to wind the fabric being delivered by roll 86. The operator then removes roll 26 from the machine.

10 A means may be provided for dropping the new mandrel 210 automatically into operative position when the filled mandrel 178 is removed. A suitable construction for this purpose is illustrated in Figs. 4 to 6, inclusive. In this embodiment when mandrel 178 is shifted outwardly along grooves 207 its pintles fall into sockets 401 on rocker arms 402 pivoted at 403 to brackets 208. The weight of the mandrel depresses arms 402 against tension springs 404 which connect extensions 405 on arms 402 with brackets 208. The engagement of stop lugs 406 with the bottoms of brackets 208 arrests the downward movement of sockets 401 and holds the filled mandrel 178 in a convenient position for removal from the machine. Latch rods 407 extend from extensions 405 along the brackets 208 and pass through guides 408 on the inner parts of the brackets into position across auxiliary grooves 211 when arms 402 are held in upward position by springs 404 as illustrated in Fig. 4.

15 While mandrel 178 is being filled replacement mandrel 210 is located in grooves 211 resting on the ends of latch rods 407 (Fig. 4). The shifting of filled mandrel 178 into sockets 401 retracts latch rods 407 and automatically drops the replacement mandrel 210 into operative position. Then the fabric is cut, the replacement mandrel started and the filled mandrel removed from the machine.

20 Our invention may also be used advantageously with fabric made up of a series of short lengths of fabric the ends of which have been fastened together. In such cases the operator employs the cutter to sever the fabric lengths at the points where they have been fastened together. When short lengths of fabric are used the cutter may not be needed.

25 By use of applicants' invention the operator may remove the filled mandrel, sever the fabric and start winding it on the replacement mandrel without stopping the machine. Applicants' invention thereby permits more rapid winding of the fabric than is possible under existing systems which require stopping the machine each time a filled mandrel is replaced.

Moreover, if a fabric steaming or finishing machine must be stopped when the filled mandrel is removed the portions of fabric in the finisher will be subjected to a more prolonged steaming and stretching than the fabric which has passed through the finisher on its way to the wind-up. This causes variations in the width of the end portions of the fabric and frequently requires cutting off such end portions with resulting loss of fabric. However by use of our wind-up apparatus the finishing machine may be kept in continuous operation thereby subjecting all portions of fabric to the same amount of steaming and stretching and assuring uniformity of width of the fabric.

We claim:

1. In a fabric winding machine having a drive roller and a mandrel on which the fabric is

wound, the improvement consisting of inclined guideways for said mandrel leading away from said drive roller and holding the mandrel in operative position therewith at a given point as the mandrel becomes filled, and communicating guideways extending upwardly from their point of junction with said guideways and permitting a replacement mandrel to drop into operative position after removal of the filled mandrel.

2. A machine as set forth in claim 1 having latch means associated with the communicating guideways retaining the replacement mandrel therein and latch releasing means actuated by withdrawal of the mandrel from operative relationship to the drive roller.

SAMUEL COHN.
JULES G. WALTER.
